UNITED STATES PATENT OFFICE.

JOHN D. LANE, OF ETHERLY, ILLINOIS.

CAB-WINDOW.

No. 869,972.

Specification of Letters Patent.

Patented Nov. 5, 1907

Application filed February 27, 1907. Serial No. 359,633.

To all whom it may concern:

Be it known that I, JOHN D. LANE, a citizen of the United States, residing at Etherly, in the county of Knox and State of Illinois, whose post-office is Watauga, Knox county, Illinois, have invented a new and useful Cab-Window, of which the following is a specification.

My invention has relation to side windows for locomotive or other engine cabs.

10 In the use of windows heretofore employed it has been difficult, in fact, practically impossible for the engineer or fireman, because of the cab being of practically the same width as that of the cars being drawn by the engine, to see to the rear without opening the 15 side window in the cab and protruding the head therethrough, which, especially in stormy weather, exposes the operator (which term shall for the purposes of this specification be hereinafter employed as referring to the engineer or fireman,) to injury, endangers the 20 sight as it subjects the eyes to injury from sparks or cinders and further exposes his person to the effects of drafts endangering his health. Also has it been difficult, because of the front window of the cab being disposed at a right angle to the line of travel of the locomotive and subjected to snow, moisture, dirt, smoke etc. begetting or clouding the pane or "light", for the 25 operator to see clearly and distinctly signals, other trains or other objects in advance. It will be evident that this has not only endangered the person and lives 30 of the enginemen, but that it rendered unsafe the lives of all other trainmen and passengers.

The primary object of my invention is to provide a means whereby the operator may conveniently and with safety, security and absoluteness, and without 35 endangering himself in any manner, see clearly and distinctly to the front, to the rear or to the side from his ordinary position in the cab, and because of the angularity of which, a means from which the aforementioned objectionable matters will be blown therefrom 40 instead of collecting thereon. This I accomplish by means of the employment of a sash or sashes arranged diagonally or obliquely to the plane of the cab frame.

A further object is to preclude any of the aforesaid undesirable substances from entering the cab from 45 above or below to the hindrance of its occupants.

A still further object is to provide means of the character stated which may be folded into a small compass and out of the way when the engine is not on the road, while a still further object is to provide simple means 50 whereby the device may be readily removed from the engine.

Other objects will hereinafter appear as the nature of the invention is better understood.

It may here be stated that the device is equally applicable to "road" or "yard" engines, and that the 55

motive power, whether steam, electricity, air or other is immaterial.

In the accompanying drawings, in which like numerals refer to corresponding parts in the several figures thereof; Figure 1 is a perspective, partly broken away, 60 showing my improvements in place on a fragment of an engine cab; Fig. 2, a detail, a plan, showing the sashes and their fastenings; Fig. 3, a detail, seen from below, showing the sashes and fender in folded positions; Fig. 4, a detail, a rear elevation, showing by full 65 lines the fender in position when in use, and by dotted lines the same when folded against one of the sashes; Fig. 5, a detail, illustrating the position when folded against one of the sashes, and Fig. 6, a detail, a sectional elevation, showing the manner of folding the 70 hood when not in use, the fender not being shown.

Referring to the aforesaid drawings, 1 indicates the sides of a cab window frame, and 2, the cab roof.

3, 3 are ordinary window sash frames, each provided with a transparent pane 4, and are hinged at 5 to fold together as shown at Figs. 3 and 6. One sash is hinged to the cab frame at 6 and the other carries hooks 7 adapted for engagement with eyes 8 on the opposite side of the frame 1. To one of the sashes 3 is hinged at 9 a fender 10 which, when not in use, is adapted to fold upwardly 80 against the sash to which it is hinged. The fender is preferably of sheet metal, and effectually precludes sand, gravel, dirt, dust, drafts of air or other deleterious substance or thing from being drawn up from below when the engine is at speed. Its edge lies preferably 85 when in use on the usual arm-rest of the cab, (not shown,) but may be supported in any other suitable manner. It is, as shown, triangular in form to correspond with and fit snugly within the lower sash members. Fixed to the tops of the sashes is one end of a 90 hood or shield 11 of flexible waterproof material, as rubber cloth, the other or free end of which extends inwardly and upwardly through the window opening and is provided with straps 12 of resilient material, which straps are furnished at their extremities with loops 13 95 adapted to engage hooks or buttons 14 on the under side of the roof of the cab and within it. It will be evident that so constructed and arranged, nothing injurious can enter the cab from above. Neither window is exposed broadside to the elements; therefore snow or grime will 100 not lodge freely thereon.

Should it be desirable not to use the device, the hooks 7 may be readily released from the eyes 8, the loops 13 freed from the hooks or buttons 14, the fender raised and the hood or shield dropped between the sashes to 105 the position shown at Fig. 6, and the whole folded back by means of the hinges 5 to rest against the side of the cab in an evident manner.

The device is readily detached from the cab by withdrawing the pintles of the hinges 5, for changing it from 110

one engine to another, for repairs etc. It occupies but a very small space when folded, and may be readily carried from place to place. The enginemen may freely see to either the front or the rear, and are fully and completely protected from injury by reason of drafts, dirt, sparks or the elements.

Having thus set forth the nature and objects, the construction, operation and advantages of my invention, I claim as new and desire to secure by Letters Patent the following, to-wit:—

1. In a device of the character described, a cab frame provided with a window opening a plurality of sashes hinged to fold together, means for hinging one of them to the cab frame at one side of the window opening, means for removably securing the other to the frame at the other side of said opening, the combined area of the two sashes when in the bowed position thus formed being greater than that of the window opening, and a flexible hood fixed to the upper portions of the sashes, it being adapted to pass through the window opening and to be secured to the interior of the cab.
2. In a device of the character described, a cab frame provided with a window opening a plurality of sashes hinged to fold together, means for hinging one of them to the cab frame at one side of the window opening, means

for removably securing the other to the frame at the other side of said opening, the combined area of the two sashes when in the bowed position thus formed being greater than that of the window opening and a fender hinged to the bottom of one of the sashes and adapted to fold thereagainst when in one position, and to cover the space between the lower sash rails when in another position.

3. In a device of the character described, a cab frame provided with a window opening a plurality of sashes hinged to fold together, means for hinging one of them to the cab frame at one side of the window opening, means for removably securing the other to the frame at the other side of said opening, the combined area of the two sashes when in the bowed position thus formed being greater than that of the window opening a flexible hood fixed to the upper portions of the sashes, it being adapted to pass through the window opening and to be secured to the interior of the cab, and a fender hinged to one of the sashes and adapted to fold thereagainst when in one position, and to cover the space between the sash rails when in another position.

In witness that I claim the foregoing as my invention I hereto subscribe my name in presence of two witnesses.

JOHN D. LANE.
